UNITED STATES PATENT OFFICE.

ELIAS HAIMAN, OF CLEVELAND, OHIO.

SWINGLETREE OR DOUBLETREE.

SPECIFICATION forming part of Letters Patent No. 790,727, dated May 23, 1905.

Application filed November 7, 1904. Serial No. 231,649.

To all whom it may concern:

Be it known that I, ELIAS HAIMAN, a citizen of the United States, residing at Cleveland, in the county of Cuyahoga and State of Ohio, 5 have invented certain new and useful Improvements in Swingletrees or Doubletrees; and I do declare that the following is a full, clear, and exact description of the invention, which will enable others skilled in the art to which 10 it appertains to make and use the same.

My invention relates to swingletrees and doubletrees, and is an improvement on the construction set forth in Letters Patent of the United States issued to me April 18, 1904, 15 and numbered 757,866.

In the accompanying drawings, Figure 1 is a plan view of my improved swingletree or doubletree bar. Fig. 2 is a rear view of one end of the bar enlarged, and Fig. 3 is a cross- 20 section thereof on a line corresponding to $x-x$, Fig. 1. Fig. 4 is a plan view of one end of a modification of the bar, and Fig. 5 is a rear edge elevation of the construction shown in Fig. 4.

25 As thus shown, A represents a swingletree or doubletree, as either may be wanted, and is referred to herein as a "bar" or "draft-bar." The bar shown in Fig. 1 is formed from a single strip of heavy sheet metal, preferably steel, 30 cut to the required shape and size and bent longitudinally to give it a substantially U shape in cross-section between its ends; but in this instance and for the purpose of the present improvement having the sides a of the 35 ends brought flat together, as seen at $a-a$, Fig. 2, and extending back to diagonal line $y-y$, Fig. 1.

Now in order to make engagement with the hooks C more convenient or accessible than 40 in the former construction above referred to, as well as to render such engagement most effective against accidental displacement of the trace-chain or other attachment D, I provide for entering the eye c of the hook through 45 a notch c' , formed in the rear edge of the bar and which is inward from the end of the bar and the eye c relatively, as shown, and opens into an inclined internal slot or channel c^2 , through which passage into eye c is obtained.

The said slot or channel c^2 extends past notch 50 c' at its upper end under projection c^3 , so as to form a trap or catch within said projection and in which the attachment D will generally be caught if it should be accidentally thrown out past the inwardly-turned point c^3 of the 55 hook. This makes a construction which renders engaging and disengaging of attachment D comparatively easy by hand, but safe and secure as against accidental release.

In Figs. 4 and 5 I show a modification of 60 the invention in which the hook portion C' is constituted a separate piece or part riveted in between the flattened sides a' at the ends of the bar A and when in place constituting a fixed and permanent portion thereof the same 65 as integral hook C. Otherwise all the details of the hook are identically the same as in Fig. 1, and the hook in both cases springs from the front of the bar and extends rearward and has its extremity running inward 70 past the outer edge a or a' and terminating on one side of inclined channel or slot c^2 within and past the entrance-notch c' . This forms a substantially keyhole construction in what may be regarded as the hook portion proper 75 of the bar for entering, releasing, and confining the attachment D.

A clevis E or other connecting part is fixed between the sides of the bar A at its middle by means of a rivet or other suitable means. 80

It will be noticed as a feature of this construction of draft-bar that the U-shape formation thereof extends into the base of the hook and terminates in the extreme end of the bar, 85 so that the hook has the advantage of this formation for its own strength under excessive strain, and the flattened portion of the bar comes mostly at that point where there is no real strain upon the hook.

What I claim is—

1. As a new article of manufacture, a draft-bar formed from sheet metal bent into substantially U shape in cross-section between its ends and having its ends flattened and formed with hooks and inclined slots leading 95 to the hooks and notches in the rear edges of the bar open to said slots between the ends thereof.

2. A draft-bar U shape in cross-section and having the rear portion of its ends pressed flatwise together and provided with a hook having its entrance through said flattened 5 portion and the swell of the bar terminating in the base of the hook, thereby strengthening the hook at its point of greatest strain.

In testimony whereof I sign this specification in the presence of two witnesses.

ELIAS HAIMAN.
